UNITED STATES PATENT OFFICE.

HENRY GRAVILLE BENNETT AND IVO ROWE, OF SHEFFIELD, ENGLAND.

SHARPENER FOR KNIVES AND OTHER CUTTING TOOLS.

Application filed May 7, 1923. Serial No. 637,110.

To all whom it may concern:

Be it known that we, HENRY GRAVILLE BENNETT and Ivo Rowe, both of 41 Eyre Lane, Sheffield, in the county of York, England, and both subjects of the King of Great Britain and Ireland, have invented certain new and useful Improvements in Sharpeners for Knives and Other Cutting Tools, of which the following is a specification.

This invention relates to sharpeners for knives and other cutting tools of the kind in which the cutting edge is passed between two hardened steel or other members disposed in V fashion.

The object of this invention is to construct an improved tool of this type.

According to this invention a sharpener for knives and other tools having a cutting edge comprises a holder and a plurality of blades positioned in said holder with all their extremities at one end attached to said holder by a common connector and the other extremities of alternate blades spaced apart and secured by common connectors to said holder, thereby collectively constituting a V like structure.

Referring to the drawings filed herewith:

Fig. 1 is an elevation of one form of knife sharpener made in accordance with this invention.

Fig. 2 is a plan.

Fig. 3 is a detail view showing one of the hardened sharpening members.

Fig. 4 is an end elevation of a modified form.

Fig. 5 is a detail view of a modified form of lug for securing the device to a base.

In Figs. 1 to 3, a holder *a* is formed with two cheeks *b*, *b* forming a recess *c* and a flange *c*¹. In the recess is secured a plurality of hardened steel blades *d*, *d* fastened by rivets or pins *e*, *e* or the like at three triangular points in the holder, one end of each blade being secured at an apical point, thereby forming a series of V shaped sharpening edges between which the knife is passed. The holder is formed with a gap to expose the V's formed by the inner edges of the blades. To ensure a good sharpening effect, an acute V is essential and to attain this, one hole *f* (Fig. 3) at one end of each blade is provided purposely out of line with the longitudinal axis of the blade, each such end being secured at the apical

point of the V so that the said apical point is disposed in the inside of the V formed by the longitudinal axes of the blades, whereby the blades are connected eccentrically at the apical point to produce an acute V relatively to a predetermined width of the open ends of the V. *g* is a handle formed of a strip of metal folded on itself and embracing and secured to the holder *a* by a pin *h* passing through the flange *c*¹ and by the pin *e* on which the blades are mounted passing through the ends of the handle. The ends of the handle are bent to form lugs *j* by which the device is secured to a base *k* by screws *m*.

The blades *d*, *d* being loosely mounted, a reasonable amount of play is produced which adds considerably to the sharpening effect whilst readily permitting displacement of particles removed by sharpening.

Fig. 4 shows a modified construction in which the blades *d*, *d* are secure at the apical point centrally instead of eccentrically and by varying the length of the blades or the width of the open end of the V, or both, any desirable angle of V can be produced.

In Fig. 5, a modified form of lug for securing the device to a base is illustrated, said lug *n* being secured, one on each side of the holder, by the pin *e* at the apical point as in the case of the lugs *j* shown in Figs. 1 and 2 and with this particular form of lug, the handle *g* may be dispensed with if desired.

What we claim and desire to secure by Letters Patent is:—

1. A sharpener for knives and other tools having a cutting edge, comprising a holder having spaced side members, and a plurality of blades associated with said holder to collectively constitute a V-like structure, one end of each of said blades being connected to said holder by a common pin-like member, and the opposite ends of alternate blades being spaced apart and connected by common pin-like members to said holder, all said pin-like members being passed through the sides of the holder, and each of said holder-sides having a V-shaped gap corresponding with said V-like structure.

2. A sharpener for knives and other tools having a cutting edge, comprising a holder, and a plurality of blades associated with said holder to collectively constitute a V-like structure, one end of each of said blades

- being secured to said holder by a common connector and the opposite ends of alternate blades being spaced apart and secured by common connectors to said holder, said connector at the apex of the V-like structure being eccentrically disposed relatively to the longitudinal centre line of each blade.
3. A sharpener for knives and other tools having a cutting edge, comprising a holder having spaced side members, and a plurality of blades associated with said holder between its sides to collectively constitute a V-like structure, one end of each of said blades being secured to said holder by a common connector, and the opposite ends of alternate blades being spaced apart and secured by common connectors to said holder, said blades being loosely mounted on said connectors, all the connectors being passed through the sides of the holder, and each of said holder-sides having a V-shaped gap complementary to said V-like structure.
4. A sharpener for knives and other tools having a cutting edge, comprising a holder, and a plurality of blades positioned in said holder with all their extremities at one end attached to said holder by a common connector and the other extremities of alternate blades spaced apart and secured by common connectors to said holder, thereby collectively constituting a V-like structure, the

holder being formed with a gap to expose the V's formed by the inner edges of the blades, a handle formed of a strip of metal folded on itself, embracing and secured to the holder, one connector on which the blades are mounted passing through the handle, a base, and means for securing the handle to the base.

5. A sharpener for knives and other tools having a cutting edge, comprising a holder composed of a plate bent on itself to form a loop at one end, upstanding sides about the loop, and a flange at the other end, a handle attached to said flange, and a plurality of blades associated in the holder-loop to collectively constitute a V-like structure, one end of each of said blades being connected to said holder by a common headed pin-member, and the opposite ends of alternate blades being spaced apart and connected by common headed pin-members to said holder, all said blades being loosely mounted on said members which are all passed through the sides of the holder with their heads overlying and engaging such sides, and said holder-sides having a V-shaped gap complementary to said V-like structure.

In testimony whereof, we affix our signatures.

HENRY GRAVILLE BENNETT.
IVO ROWE.
